UNITED STATES PATENT OFFICE.

ARISTIDES CALCAÑO, OF LA GUAIRA, VENEZUELA.

STATIONERY.

1,359,326.

Specification of Letters Patent. Patented Nov. 16, 1920.

Application filed October 4, 1919. Serial No. 328,568.

To all whom it may concern:

Be it known that I, ARISTIDES CALCAÑO, a citizen of Venezuela, and resident of La Guaira, Venezuela, have invented certain 5 new and useful Improvements in Stationery, of which the following is a specification.

My invention is an improvement in stationery, and has for its object to provide a 10 combined envelop and inclosure, formed from a single blank having lines of partial separation and lines of adhesive for permitting the sheet to be folded into a letter and an envelop for the letter.

15 In the drawings:

Figure 1 is a plan view of one of the blanks;

Fig. 2 is a similar view showing the letter folded;

20 Fig. 3 is a plan view, showing the envelop folded, with the exception of the seal flap;

Fig. 4 is a similar view with the envelop completely folded, stamped and ready for transmission.

25 In the embodiment of the invention shown, a pad is provided, consisting of a number of similar sheets 13, the said sheets being arranged one upon the other, and they may be connected at one end by an adhesive

30 in the usual manner. The sheet 13 is partially divided by alined lines of partial separation 14 and 15, extending transversely of the sheet approximately one-third the distance from the upper end, and these lines

35 of partial separation extend inwardly from each edge, being formed by perforations or in any other suitable or desired manner. The line 14 of partial separation is about one-half the length of the line 15, which is

40 the same length as the distance between the adjacent ends of the lines 14 and 15.

The arrangement is such that when that portion of the sheet below the line of partial separation 15 is separated and folded

45 over upon the remainder of the sheet, the free edge of the said portion will be flush with the inner end of the line 14. A third line of partial separation 16 is provided, extending from the line 15 to the top of the 50 sheet, parallel with the side edges of the sheet, and at a predetermined distance from the adjacent edge.

Taking the sheet shown in Fig. 1, which has a width of three and three-quarter 55 inches, which may be considered as fifteen

quarter inches, and taking the quarter inch as a unit, the line 14 will have three units, the line 15 six units and the distance between the lines 14 and 15 six units.

The line 16 is spaced from the adjacent 60 edge a distance of two units.

In use, the letter is written on that portion of the sheet below the lines 14—15, and the full width of the sheet may be used, or merely that space comprised between the 65 vertical lines dropped from the adjacent ends of the lines 14—15 of partial separation. The letter may be written on the typewriter or by hand, as may be desired, and it will be evident that there is nothing to 70 prevent the insertion of the sheet in a typewriting machine in the usual manner. After the letter is written that portion of the sheet containing the letter and below the lines 14—15 is separated from the right 75 hand edge to the inner end of the line 15, to form a flap which is folded smoothly over on to the body.

Now that portion of the sheet below the line 14 is separated to form a flap which 80 is folded smoothly over upon the first named flap. The bottom half of the folded portion is now doubled over upon the upper half, as indicated in Fig. 2. That portion of the sheet above the line 14 of partial separation 85 is provided at the adjacent side edge with a line of adhesive 17 for sealing the inclosure in a manner to be presently described. In addition to the lines of partial separation 14—15—16 that portion of the sheet outside 90 of the line 16 is provided with two lines of partial separation 18, which converge from the line of partial separation 16 to the free edge of the sheet.

It will be evident that when the sheet is 95 separated on these lines 18 a tongue 19 will be formed. Just inside the line 16 a vertical slot 20 is provided, and another slot 21 is arranged in the line of adhesive, the said slots or slits being parallel.

When the envelop portion is folded as above described, and as shown in Fig. 3, the tongue 19 is passed through the slot 21 and tucked into the slot 20, as shown in Fig. 4. When now a stamp indicated at 22 is placed 105 over the tongue and the two slots 20—21, the envelop will be sealed, so that it cannot be opened without destroying the stamp.

The line of partial separation 16 permits the inclosure or envelop to be easily opened, 110

and it will be noticed that this line is just below the outer edge of the sealing flap 9 when the said flap is folded.

I claim:

- 5 A combined letter sheet and envelop comprising a rectangular blank having lines of partial separation extending from its opposite edges toward the center at approximately one-third the distance from one end,
- 10 one of said lines being of greater length than the other and the sheet being adapted to be separated at the said lines and to have its side edges folded over upon each other, with the wide side edge beneath the narrow
- 15 side edge and then to be doubled trans-

versely and folded onto the remainder of the sheet, the remaining portion of the sheet having at one side edge a line of adhesive and the said side edges being adapted to be folded over upon each other over the folded letter sheet to form the envelop, with the wide side as a back flap and the narrow side as a sealing flap, the sides of the said upper portion having slots spaced inwardly from the side edges and parallel therewith and one side having lines of partial separation to define a tongue insertible outwardly through the slot in the sealing flap and inwardly through the slot in the back flap.

ARISTIDES CALCAÑO.
